UNITED STATES PATENT OFFICE.

WILLIAM THOMAS BROWN, OF HAPEVILLE, GEORGIA.

LOCOMOTIVE-HEADLIGHT.

1,138,449.

Specification of Letters Patent.

Patented May 4, 1915.

Application filed August 18, 1914. Serial No. 857,374.

To all whom it may concern:

Be it known that I, WILLIAM THOMAS BROWN, citizen of the United States, residing at Hapeville, in the county of Fulton and State of Georgia, have invented certain new and useful Improvements in Locomotive-Headlights, of which the following is a specification.

This invention relates to an improvement 10 in locomotive headlights, and the object is to provide means for throwing the reflection or projecting a shaft or beam of light at an angle to the direction taken by the shaft or beam of light from the headlight. 15 By such an arrangement it is possible to observe the movements of a train from points or localities where the train is not observable, yet by the stream of light, it is possible to determine approximately the location of 20 the train, and in case of accident, to take the necessary precautions to prevent the wrecking of the approaching train.

The invention relates to still other novel 25 features of construction and combinations of parts which will be hereinafter more fully described and pointed out in the claims.

In the accompanying drawings: Figure 1 is a perspective view of a reflector showing the invention applied thereto; Fig. 2 is a perspective view of the secondary reflector 30 holder; Fig. 3 is a perspective view showing the secondary reflector holder applied to a secondary reflector; and Fig. 4 is a plan view of a modified form of secondary reflector; Fig. 5 is a central vertical section.

A represents the reflector to which the invention may be applied. This reflector is provided with openings 1 and 2 through which the chimney (not shown) of a lamp 40 projects. A concave secondary reflector 3 is supported upon the frame, consisting of the central member 4 with arms 5, 5 radiating therefrom. These arms extend to the edge of the secondary reflector 3, and the 45 ends of the arms are received in orifices 6 in the peripheral edge of the secondary reflector. At one terminus of the central member 4, a hook 7 is formed, which extends through the opening 1 and engages the reflector A for supporting the frame thereon. A right-angular strip or portion 8 extends from the central member 4, and is fastened to the rim 9 of the reflector. 50

In Fig. 4, I have shown a slightly modi-

fied form of secondary reflector, a portion 55 being cut away at one end, as at 10, and opposite to the cut portion 10, a recess 11 is formed. A secondary reflector of this character is sometimes necessary, so that the recessed portion will fit upon the chimney, 60 but the result obtained is the same. By applying a secondary reflector to a reflector, the angle of which can be regulated by the flexible arms 5, as they can be readily bent to bring the reflector to the desired angle, 65 two streams of light can be thrown, one directly from the reflector A, and the other in an upward direction, and preferably at an angle of approximately 45°.

From the foregoing, it will be seen that I 70 have provided a very simple arrangement for attaching a secondary reflector to a reflector for the purpose of projecting a stream or shaft of light from the reflector in a direction at an angle to the main stream 75 of light projected from the reflector.

I claim:

1. The combination with a reflector, of a frame removably supported thereon, and a secondary reflector removably mounted on 80 the frame for throwing a stream of light at an angle to the stream projected by the reflector.

2. The combination with a reflector, having openings therein through which a chimney may extend, of a frame mounted on the reflector having an end passing through one of the openings for supporting the frame upon the reflector, and a secondary reflector carried by the frame for throwing a stream 90 of light in a direction at an angle to the stream of light projected from the reflector.

3. The combination with a reflector, of a secondary reflector supported in the reflector for throwing a stream of light at an angle 95 to the stream projected by the reflector, and a flexible frame mounted in the reflector for supporting the secondary reflector, and adapted to be flexed to accommodate the angle to which the secondary reflector is to 100 be adjusted.

In testimony whereof I affix my signature, in the presence of two witnesses.

WILLIAM THOMAS BROWN.
